[57] CLAIM

The ornamental design for a diskette drive front panel, as shown and described.

DESCRIPTION

FIG. 1 is a right, top, front perspective view of the diskette drive front panel showing our new design; FIG. 2 is a front elevational view thereof on an enlarged scale;

FIG. 3 is a rear elevational view thereof on an enlarged scale;

FIG. 4 is a right side elevational view thereof on an enlarged scale;

FIG. 5 is a left side elevational view thereof on an enlarged scale;

FIG. 6 is a top plan view thereof on an enlarged scale;

FIG. 7 is a bottom plan view thereof on an enlarged scale.
